(57) **CLAIM**

I claim the ornamental design for an electronic grill for oven, as shown and described.

DESCRIPTION

FIG. 1 is a front perspective view of an electronic grill for oven showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an exploded perspective view thereof;

FIG. 10 is another front perspective view thereof, in which an oven is provided in broken lines to illustrate an example environment;

FIG. 11 is an enlarged view of the dot-dot-dash broken line encircled portion in FIG. 1;

FIG. 12 is an enlarged view of the top portion of the electronic grill for oven; and,

FIG. 13 is an enlarged cross-sectional view of the dot-dot-dot-dash broken line encircled portion in FIG. 1.

The broken lines in the figures show portions of the electronic grill for oven which form no part of the claimed design.

The broken line showing of the oven in FIG. 10 is for environmental purposes only and forms no part of the claimed design.

The dot-dash broken lines represent an unclaimed boundary line and form no part of the claimed design.

The dot-dot-dash broken lines encircling a portion of the claimed design that is illustrated in the enlargement of FIG. 11 form no part of the claimed design.

The dot-dot-dot-dash broken lines encircling a portion of the claimed design that is illustrated in the enlarged cross-sectional view of FIG. 13 form no part of the claimed design.
